Garrettson Smith & Henry Brown, of Philadelphia, Pa.
Assignors to
Leibrandt McDowell & Co. of same place.
Letters Patent No. 1019. Dated June 29, 1858.

The schedule referred to in these Letters Patent and making part of the same.

To all whom it may concern:

Be it known that we, Garrettson Smith and Henry Brown, of the City of Philadelphia, and State of Pennsylvania, have invented or produced a new and original design for the plates of a Cooking Stove, termed the "Medallion," and we do hereby declare the following to be a full and exact description of the same, reference being had to the accompanying drawing, which forms a part of this Specification, and in which

Fig. 1. represents one of the side plates of the Stove.

Fig. 2, the front plate.

Fig. 3, the back plate.

Fig. 4, an outline of the Stove in perspective.

Fig. 5, a section, full size, of the moulding on the edge of the top plate,

Fig. 6, a section of the moulding on the edge of the bottom plate.

The side plate (Fig. 1.) is edged with a plain moulding a and is furnished with the oven doors A and C and fire door B, all of which have foliated ornaments and central oval mouldings of corresponding character, in alto-relievo, and all are edged with plain mouldings, with the exception of one corner of the large oven door, — where the moulding is waved. The side plate has also ornaments b and d, one below and the other above the large oven door.

The front plate (Fig. 2.) is also edged with plain mouldings — and has the usual air openings c and the doors E, E, in front of the grate, the — mouldings, foliated and oval ornaments of these doors being similar in character to those of the side plate.

The end of plate (Fig. 3) has also plain mouldings on the side and bottom, and has a central ornamented panel f and two ornamented side panels, g, e.

Des. 1019

The top plate F is plain, with the exception of a moulding represented in section (Fig. 5.) on the edge,

The bottom plate G is also plain, with the exception of a moulding (Fig. 6) on its edge.

We claim, The combination of the ornamental figures and forms represented in and by the accompanying drawing, forming together an ornamental design for the plates of a cooking stove, termed the "Medallion".

In testimony whereof, we have signed our names to this Specification before two subscribing witnesses.
